(57) **CLAIM**

The ornamental design for a fan, as shown and described.

DESCRIPTION

FIG. 1 is a top front side perspective view of a fan showing my new design;

FIG. 2 is a front view of the fan;

FIG. 3 is a left side view of the fan;

FIG. 4 is a rear view of the fan;

FIG. 5 is a right side view of the fan;

FIG. 6 is a top view of the fan; and,

FIG. 7 is a bottom view of the fan.

The jagged line shown at the end of the power cord indicates that any portion of the power cord beyond what is shown forms no part of the claimed design.
